TRIANGULAR STRAND FOR CABLES

Alexandre Chamoux, Bourg, France, assignor to
 Societe Trefilerie & Cablerie de Bourg, Bourg,
 France, a French joint-stock company

Application December 19, 1949, Serial No. 133,906
 In France December 30, 1948

5 Claims. (Cl. 57—145)

1

My invention relates to stranded cables formed of sub-strands of triangular cross-section instead of sub-strands of round cross-section as in the cables of conventional construction. Such cables have the advantage that for a given cross-sectional area their outer wearing surface is greater.

In the known cables the triangular strands are generally formed on a triangular core with round wires wound thereon. The triangular core itself is made of wires of triangular cross-section, but it has also been proposed to form such cores of a strand comprising three round wires (or three elementary circular strands made of round wires) of equal diameter twisted with three intermediate round wires (or strands) of much smaller diameter which are so disposed as to fill the three spaces between the successive wires of larger diameter to form a triangular profile.

A first object of my invention is to provide a cable formed of triangular strands which cable will contain no triangular profile wire.

Another object of my invention is to provide a triangular cable strand wherein at least the core will comprise round wires of the same diameter and wherein each longitudinal edge of the triangular shape will be formed of the same wire throughout its length.

Still a further object of my invention is a triangular cable strand comprising a core formed of a strand of circular cross-section and of three round wires wound thereon in equally spaced relation.

I may for instance form a circular strand with an axial wire and with six wires spirally wound thereon. By winding on such a strand with a different pitch three equidistant wires of the same diameter as the wires of the core there is obtained a composite strand having a cross-section in the form of an equilateral triangle with rounded apexes. Such a triangular strand may be used as such, or it may preferably form a core whereon there is wound one or several layers of round wires in the known manner. It will also be understood that the inner circular strand could be formed of several layers of round wires. For instance it may comprise an axial wire, a first layer of six wires and a second layer of twelve wires. In such a case the three outer wires must be of a somewhat larger diameter than the wires of the inner strand.

In any case the winding pitch of the three outer wires of the triangular strand or core should be equal to the winding pitch of the strand in the final cable, as it will be evident, in order that the strand may exactly fill a sector in the cable structure.

2

In some cases I may select the respective diameters of the three wires in such a manner that one side of their triangular outer profile will be somewhat convex to remain parallel to the circular outer profile of the core, while the two other sides of the said triangular profile are straight. Such an arrangement is of advantage when such strands form outer members for a larger cable to provide for the finished cable a cylindrically curved outer surface while leaving straight mutual contacting inner faces for the successive triangular strands forming the cable.

In the annexed drawings:

Fig. 1 is a cross-section showing a triangular strand or core established in accordance with my invention.

Fig. 2 shows another embodiment of such a triangular strand.

Fig. 3 is a side view of the triangular strand of Fig. 2, the successive layers being cut back to show the inner construction of the strand.

Fig. 4 is a cross-section of a cable formed of strands of the kind of Figs. 2 and 3.

Fig. 5 shows another embodiment of my improved triangular strand.

Fig. 6 illustrates a modification of the strand of Fig. 5, wherein one of the sides of the triangular profile is convex.

The triangular core illustrated in Fig. 1 comprises a circular strand of conventional construction formed of an axial wire 1 and of six outer wires 2 disposed around wire 1 in close regular formation, wires 1 and 2 being of the same diameter. On the circular strand thus formed there is spirally wound a set of three wires 3 in spaced equidistant relation, the said wires 3 being round and of the same diameter as wires 1 and 2. The winding pitch of wires 3 is much greater than the pitch of wires 2 in such a manner that wires 3 do not fit into the intermediate spaces or depressions between the successive wires 2 but are wound on the circumference which forms the outer profile of the strand 1—2, such circumference being indicated at 4 in Fig. 1.

It will be seen that under such conditions wires 3 determine with the core a profile in the form of an equilateral triangle 5, the sides of such triangle being tangent to circumference 4.

The triangular core thus obtained is preferably not used as such in the construction of a cable, but there is wound thereon one or several layers of round wires 6 (Figs. 2 and 3) which may be of the same diameter as wires 1, 2 and 3 or of another diameter. The winding pitch of these outer layers is of course different from the pitch of wires 3; in the case illustrated it is the same

as the winding pitch of wires 2, but this is in no way necessary.

The triangular strand thus established is used in the conventional manner to form a cable by winding a plurality of such strands around an appropriate core with a pitch equal to the pitch of wires 3, six being the number generally selected owing to the equilateral form of the elementary strands. Fig. 4 shows such a cable.

It will be understood that my invention thus permits the construction of a triangular strand cable containing triangular profile wires, as hitherto generally used. Moreover it is formed of wires having the same diameter, which facilitates manufacture.

In the embodiment of Fig. 5 the triangular strand comprises a circular core formed of nineteen round wires of the same diameter, namely: an axial wire 11, a first layer of six wires 12a and a second layer of twelve wires 12b wound on the first layer with a different pitch, generally with a pitch opposed to the former. On this inner circular strand there are wound three round wires 13 of a somewhat larger diameter, such wires being in spaced equidistant relation to determine an equilateral profile with the sides of the triangle tangent to the circumference of the inner circular core. The difference in diameter between wires 13 and wires 11, 12a or 12b is relatively small. Of course wires 13 are wound with a pitch different from wires 12b.

On the triangular strand thus obtained there is wound an outer layer of round wires 17.

It is sometimes convenient to have for the strand an outer profile somewhat departing from the triangular profile, that is, one side being more or less convex. This is easily obtained by selecting two wires 23a, of a somewhat smaller diameter than the third one 23b as indicated in Fig. 6. The strand thus obtained has one convex curved side which is particularly well adapted to form part of the outer profile of the final cable, as will be apparent for those skilled in the art. The wires 22a, 22b, and 27 in Fig. 6 correspond in arrangement with the wires 12a, 12b and 17 of Fig. 5.

Although I have described triangular strands of substantially equilateral profile, it should be understood that by properly selecting the respective diameters of the three wires 3 any other triangular profile may be obtained, for instance corresponding to five strands in the finished cable, or to more than six. In each particular case I determine the required triangular profile to give a circular outer profile coaxial with the circular profile of the inner core; and I thereby determine the diameters of the three intermediate wires to be used so as to create the necessary angular portions of these triangular strands which are wound exterior to the core.

I claim:

1. A triangular strand for cables comprising an inner circular core; and three wires of circular cross-section spirally wound on said core in equally spaced relation, said wires being of such a diameter as to determine a triangular outer profile substantially tangent to the circular

profile of said core; the inner circular core being formed of a circular strand of wires, and the outer layer of said circular strand having a winding pitch substantially different from the pitch of the three wires wound on said inner circular core.

5 2. A triangular strand for cables comprising an inner circular core; and three wires of circular cross-section spirally wound on said core in equally spaced relation, said wires being of such a diameter as to determine a triangular outer profile substantially tangent to the circular profile of said core; and an outer layer of wires wound on said three wires with a pitch 10 substantially different from the winding pitch of said three wires.

20 3. A triangular strand for cables comprising an axial wire, six wires having the same diameter as said axial wire and spirally wound thereon in contacting relation; three wires having the same diameter as said axial wire and spirally wound on said six wires in equally spaced relation and having a pitch substantially different from the winding pitch of said six wires; and an outer layer of wires wound on said three wires with a pitch substantially different from the winding pitch of said three wires.

25 4. A triangular strand for cables comprising an axial wire; six wires having the same diameter as said axial wire and spirally wound thereon in contacting relation; twelve wires also having the same diameter as said axial wire and spirally wound on said six wires in contacting relation with a pitch substantially different from the winding pitch of said six wires; three wires wound on said twelve wires in equally spaced relation, said three wires being of such a diameter as to determine a triangular outer profile substantially tangent to the circular profile of the layer formed by said twelve wires; and an outer layer of wires wound on said three wires with a pitch substantially different from the winding pitch of said three wires.

35 5. A triangular strand for cables comprising an inner circular core and three wires of circular cross-section spirally wound on said core in equally spaced relation, said three wires being of such respective diameters as to determine an outer profile in the form of a triangle with two straight sides and a convex side, the said profile being substantially tangent to the circular profile of said core.
